A. P. SAVAGE,

SHOES

APPLICATION FILED AUG. 18, 1916

1,322,678.

Patented Apr. 17, 1917.

Adelia P. Savage,

Inventoz;

Attorney

UNITED STATES PATENT OFFICE.

ADELIA P. SAVAGE, OF SIDNEY, OHIO.

SHOE.

1,222,678.

Specification of Letters Patent. Patented Apr. 17, 1917.

Application filed August 13, 1916. Serial No. 115,572.

To all whom it may concern:

Be it known that I, ADELIA P. SAVAGE, a citizen of the United States, residing at Sidney, county of Shelby, and State of Ohio, have invented certain new and useful Improvements in Shoes, of which the following is a specification.

My invention relates to shoes and particularly to means for rendering the shoes waterproof at their meeting or fastening edges.

The object of my invention is to provide in a shoe, means to prevent water or moisture entering the shoe where the uppers of the shoes are fastened; that is to prevent the water or moisture entering between the meeting or fastening edges.

A further object of my invention is to provide in a shoe, waterproofing means as mentioned which shall not detract from the appearance of the shoe or the comfort of the same to the wearer.

A further object of my invention is to provide waterproofing means as mentioned which shall not add materially to the cost of production of the shoe. Other objects will appear hereinafter.

With these objects in view my invention consists generally in providing the adjacent faces of the overlapping edges of the upper with strips of material, the surfaces of which have a tendency to adhere. My invention further consists in providing a padding between the faces of the edges of the upper and the aforementioned strips whereby the latter are maintained in close contact when the shoe is being worn. My invention further consists in providing the overlapping edges, equipped as mentioned, with suitable fasteners for securing the shoe and for holding said strips in proper contact. My invention further consists in various details of construction and arrangements of parts, all as will be fully described hereinafter and particularly pointed out in the claims.

My invention will be more readily understood by reference to the accompanying drawings forming a part of this specification and in which,

Figure 1 is a perspective view of a shoe embodying my invention.

Fig. 2 is a fragmentary detail view of the meeting edges of the upper,

Fig. 3 is a section on substantially the line 3-3 of Fig. 1.

Fig. 4 is a perspective view of a portion of one of the meeting edges illustrating the

waterproofing and padding strips partially removed, and

Fig. 5 is a section similar to Fig. 3 illustrating my invention as applied to a laced shoe.

Referring now to the drawings 1 indicates a shoe having the usual upper 2 provided with the ordinary overlapped edges 3, such as is common in the construction of buttoned shoes. The adjacent faces of the edges are provided with strips of material having a tendency, when brought into intimate contact, of adhering, such as fine grained rubber or the like. Between the strips 4 and 5 the faces of the upper 2 are arranged strips of padding 5. This padding may be of any preferred material but I find a thin cotton felt efficient for the purpose.

Any preferred form of fastening means 75 may be employed but I prefer to secure the edges of the upper by means of the ordinary snap fasteners 6, as illustrated in Figs. 1 to 4 inclusive, in which event the elements of the fasteners are secured through the strips 4 and 5 and the adjacent portions of the upper. Preferably, the fasteners are secured so that the ball and socket portions are slightly embedded in the waterproofing strips as shown clearly in Fig. 3, so that when the fasteners are secured the strips 4 will be held firmly in contact throughout substantially their extent.

In applying my invention to a laced shoe the inner faces of the edges of the upper 90 are provided with the strips 4 and 5 as above described, and the tongue 7 is provided, on its outer surface with a facing 8 of material similar to the strips 4, as illustrated in Fig. 5. If desired a padding strip 9 may be arranged between the tongue and the facing 8.

It is obvious that, with a shoe equipped with my invention, it is impossible for water or moisture to enter the shoe at the meeting or fastening edges of the upper, as to do so it must enter between the strips 4 and 5 and this is practically impossible owing to the nature of the said strips which causes them to normally adhere and the padding 5 which holds said strips into proper engagement. It is also obvious that, as the waterproofing strips are very thin and are arranged between the meeting edges, they are practically invisible and do not detract from the appearance of the shoe. Also my invention 110 may be applied to shoes without materially increasing the cost of the same.

I claim:—

1. A shoe comprising an upper having overlapping edge portions, strips of material having a tendency toward mutual adherence on the adjacent faces of said edge portions, and fastening means adapted to hold said strips in engagement.
2. A shoe comprising an upper having overlapping edge portions, strips of material having a tendency toward mutual adherence on the adjacent faces of said edge portions, resilient material arranged between said strips and the respective edge portions, and fastening means adapted to hold said strips in engagement.
3. A shoe comprising an upper having overlapping edge portions, strips of material having a tendency toward mutual adherence on the adjacent faces of said edge portions, and snap fastenings secured

through said strips and said edge portions, substantially as described.

4. A shoe comprising an upper having overlapping edge portions, strips of material having a tendency toward mutual adherence on the adjacent faces of said edge portions, strips of resilient material arranged between said strips and the adjacent edge portions, and snap fastenings secured through said strips and the adjacent portions of the upper, substantially as described.

In testimony whereof I have signed my name to this specification in the presence of two subscribing witnesses.

ADELIA P. SAVAGE.
